UNITED STATES PATENT OFFICE.

CHARLES O. BARKS, OF BIRMINGHAM, ALABAMA.

STOCK DISTRIBUTOR FOR BLAST-FURNACE TOPS.

Application filed December 26, 1922. Serial No. 608,811.

To all whom it may concern:

Be it known that I, CHARLES O. BARKS, a citizen of the United States of America, residing at Birmingham, in the county of Jefferson and State of Alabama, have invented certain new and useful Improvements in Stock Distributors for Blast-Furnace Tops, of which the following is a specification.

10 My invention relates to a new and improved means for the effective distribution of stock as it falls from the little bell onto the large bell of a blast furnace charging top.

15 It has for many years been the opinion of many of the most experienced blast furnace operators that improved results will be obtained from the furnace if the stock can be charged so as to fall in piles with 20 the coke effectively enveloping the ore in each pile, the theory being that by such an arrangement of the stock in the furnace a more uniform flow of air and gas through the stock is obtained and more even and 25 efficient smelting of the charge results.

I have sought in my present invention to devise the simplest and most effective means for the deposit on the big bell of the stock in piles which will be discharged thereby in the furnace and to this end I interpose between the little or upper bell and the big or lower bell a series of spaced deflectors, rigidly attached to the hood or jacket and disposed to split the flow of stock so that it 30 will be distributed in a series of distinct and separate piles on the big bell, in each of which piles the material, according to its specific gravity and angle of repose, will assume its proper position.

35 My deflectors are especially designed to be easily installed and repaired so that the present types of furnace tops may be equipped with them and the deflectors maintained at negligible expense.

40 My invention will be better understood by reference to the accompanying drawings which illustrate it in its preferred embodiment only.

The drawings in—

45 Fig. 1 shows a vertical cross-sectional view through a typical furnace top structure equipped with my invention.

Fig. 2 is a partial plan view taken on the line 2—2 of Fig. 1.

50 Similar reference numerals refer to similar parts throughout the drawings.

In the embodiment illustrated I show a blast furnace 1 having a lip ring 2 with which the big bell 3 co-acts and which is mounted in a hopper 4 on which is supported 60 a hood or jacket 5 in the shape of a truncated cone. A charging chute 6 is mounted in the top of the hood and is sealed at its lower end by the little or upper gas seal bell 7. The big bell 3 is operated by the rod 8 which 65 works in a sleeve 9 which, in the manner well understood in the art, will be manipulated both to reciprocate and rotate the little bell.

All of the parts as thus far described are 70 conventionally illustrated and may be of any suitable design or construction. I mount a series of distributors within the hood and in the path of the stock falling from the little bell, these distributors being preferably formed by angle irons 10 which at their outer ends are connected by gussets 11 to the hood 5, the gussets being each provided with an out-turned flange 12 which is bolted or riveted to the hood 5. The angles are 75 disposed with their apex upward and they extend from the outer wall inwardly to a point overhung by and closely juxtaposed to the small bell when it is lowered. The gussets are attached to the under faces of 80 the angles by suitable bolts or rivets and when an angle becomes worn it can be readily repaired by superposing an angle on the worn angle and bolting or otherwise connecting it thereto, thus avoiding the necessity for disturbing the gusset mounting.

The distributors are disposed at a downward inclination and are spaced a substantial distance apart sufficient to produce the 85 desired number of piles of stock of the desired size on the big bell. As illustrated, I show six of these distributors which will 90 act to split and divide the falling stream of stock from the little bell into six piles on the big bell, but it is to be understood 95 that this particular number of distributors may be varied.

In operation, when the little bell is lowered to drop the charge onto the big bell the stock will slide off the little bell and part 100 will fall straight down onto the big bell but a considerable part will strike the deflectors just after leaving the little bell and the stock which thus strikes the deflectors will have 105 almost the maximum distance to fall and can 110 therefore be deflected so as to be concentrated into and form the several piles on

the big bell. In each of these piles the larger particles of coke will tend to envelope the finer particles of ore in the pile and in each pile the stock will be more or less uniformly distributed circumferentially from the apex of the pile outwardly with the finer stock at its center and the corner stock about its circumference. When the big bell is lowered the piles will drop practically without loss of identity into the furnace where they will produce the desired operating conditions first above described.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a blast furnace top having big and little bells and a gas sealing hood between them, a series of radially disposed spaced stock deflectors rigidly mounted on the hood and disposed to split the stock falling from the little bell into individual piles on the big bell.
2. A blast furnace top in accordance with claim 1, in which the distributors are disposed at a downward inclination and project so that their inner ends are overhung by the little bell.

3. In a blast furnace top having little and big bells and a gas sealing hood between them, a series of radially disposed stock distributors formed by angle irons having gusset plates attaching them to said hood, the angles being disposed with their inner ends overhung and closely juxtaposed to the little bell when in its lowered position.

4. In a blast furnace top, a charging bell, a casing below the bell, a series of radially disposed spaced angle bars mounted on the casing and disposed in the path of the stock as it falls from said bell to deflect portions thereof and form individual stock piles.

5. In a blast furnace charging top, a lip ring and a big bell co-acting therewith, a gas sealing hood above the lip ring, a charging chute in said hood, a little bell co-acting with said chute, a series of radially downwardly inclined circumferentially spaced narrow angle irons, each having its apex upturned, and gusset plates riveted to the under faces of the sides of each angle iron at its outer end, said gusset plates having out-turned flanges which are attached to the hood in position to support the angle irons with their ends closely juxtaposed to and overhung by the little bell when in its lowered position.

In testimony whereof I affix my signature.

CHARLES O. BARKS.
